UNITED STATES PATENT OFFICE.

GARDNER E. WHEELER, OF NEW HAVEN, CONNECTICUT, ASSIGNOR TO THE ENGLISH & MERSICK COMPANY, OF NEW HAVEN, CONNECTICUT, A CORPORATION OF CONNECTICUT.

RADIATOR UNIT.

1,098,774.

Specification of Letters Patent. Patented June 2, 1914.

Application filed April 3, 1913. Serial No. 758,675.

To all whom it may concern:

Be it known that I, GARDNER E. WHEELER, a citizen of the United States, residing in New Haven, county of New Haven, and State of Connecticut, have invented certain new and useful Improvements in Radiator Units, of which the following is a full, clear, and exact description.

This invention relates to cellular or honeycomb radiators of the type commonly used for cooling automobile engines, and it has special reference to a radiator core or section composed of a plurality of elongated cellular units grouped together in such a manner as to create between them a plurality of water passages.

More particularly, my improvements relate to a construction in which the several units have shouldered or offset portions by which they are spaced from each other at the front and rear edges to present the aforesaid water passages, thereby avoiding the use of the well known spacing wires, and wherein the air passages of each unit are defined by plaits or fins bent up from the respective side walls of the unit, the fins of one wall alternating with those of the opposite wall.

In automobile radiators of the so-called "wireless" type having the above mentioned alternate arrangement of the plaits, it has heretofore been a very difficult matter to place the opposite side walls in such relation to each other that the plaits of one wall will so coöperate with those of the opposite wall as to present air passages having exactly the desired cross-sectional form. The appearance of the radiator is very much enhanced if all of the air passages are accurately uniform in shape and size, but in the past it has been a very difficult matter to obtain this result, as there has been no means for indicating whether or not the opposite side walls of each unit have the proper location with respect to each other. When the relative adjustment of the two opposite side walls is left entirely to the eye of the operator it will be found very often that the air spaces of the unit are not uniform, and in attempting to manufacture a radiator with air passages of square cross-section, the displacement of one of the side walls of a unit with reference to the opposite side wall will cause all of the passages of the unit to be

of oblong instead of square cross-section, and the adjacent passages will differ in size.

The primary object of my invention is to provide means which eliminates the above drawback and at the same time enables the free edges of the plaits or fins to be readily soldered to the opposite side wall of the unit at the shouldered or offset front and rear edges thereof, whereby the front and rear surfaces of the radiator will each present an extremely uniform group of air passages having continuous rectangular mouths.

To these and other ends, the invention consists in the novel features and combinations of parts to be hereinafter described and claimed.

In the accompanying drawing, Figure 1 is an enlarged fragmentary edge view of a radiator unit embodying my improvements, after the same has been dipped in solder. Fig. 2 is a side elevation of a portion of Fig. 1, Fig. 3 is an edge view similar to Fig. 1 showing the appearance of the unit before soldering. Fig. 4 is a fragmentary view of one of the side walls of the unit looking from the inside. Fig. 5 is a section on line 5-5 of Fig. 2, Fig. 6 is a section on line 6-6 of Fig. 2, and Fig. 7 is a section on line 7-7 of Fig. 4.

Referring to the drawing and particularly to Fig. 3, 10 is a sheet metal wall constituting one of the side walls of the unit and 11 is the opposite side wall. In the form shown, the walls 10 and 11 are formed as parts of the same strip, which is doubled over on itself, as shown at 12, but this feature is immaterial to the invention. The wall 10 is bent up at intervals to present transverse plaits 13 and the wall 11 is bent up to present similar plaits 14. These two sets of plaits are adapted to be arranged in alternating fashion, as shown in Fig. 3, so as to present in conjunction with the side walls and end walls of the unit, a plurality of air passages 15 extending horizontally from the front edge of the unit to the rear edge thereof. The construction of the rear edge of the unit is the same as that of the front edge and I have not considered it necessary to illustrate both edges.

The wall 10 is provided with a shouldered portion or offset 10* extending along the edge thereof and the wall 11 is provided

with a similar shouldered portion or offset 11^a. These offsets extend from the unit in opposite directions so as to enlarge the front and rear edges of the unit, whereby a plurality of vertical water spaces will be formed between adjacent units when such units are grouped together side by side in a manner well understood in the art. The plaits 13, 14 are of uniform width throughout their length and the main portions of the plaits 13 extend from the wall 10 into abutment with the main portion of the wall 11, whereas the plaits 14 of the wall 11 extend across to and support the main part of the wall 10 in a similar manner.

In accordance with my invention, I provide means for facilitating the manufacture of the unit by furnishing the offset portions 10^a, 11^a respectively, with teats or projections 10^b and 11^b respectively, adapted to register with the plaits or fins 14 and 13 respectively, when the side walls are properly assembled relatively to each other, as shown in Fig. 3. The teats or projections 10^b are situated at the edge of the offset 10^a at points midway of the plaits 13, and the teats or projections 11^b are similarly formed and located relatively to the wall 11 and the plaits 14. By this construction it is an easy matter for the operator to place the walls 10 and 11 in such relative positions that the air passages 15 will be of uniform cross-section throughout the length of the unit. If desired, the portions of the plaits 13, 14 which abut the main portions of the walls 11 and 10 respectively (*i. e.* those portions other than the offset portions 11^a and 10^a) may be engaged in seats 16 which are created by providing the corresponding side wall with pairs of projections 17. In the form shown, the teats or projections 10^b are formed by indentation of the metal completely across the width of the offset portion of the side wall, and the projections 17 are formed by indenting the metal from the same side. The projections 17 are shown as consisting of comparatively short ribs, but I do not limit myself to this feature, as small circular bosses or similar projections will serve to form seats for the free edges of the fins or plaits on the main portions of the side walls adjacent the offsets 10^a, 11^a.

The bottoms of the seats 16 are in line with the apices of the teats or projections 10^b, 11^b, so that the straight edge of each plait 13 or 14 may have a full continuous bearing on the opposite wall of the unit. In this manner, the cellular structure is given a maximum amount of strength to resist collapse or buckling.

The small teats or projections 10^b, 11^b not only facilitate the adjustment of the opposite side walls of the unit in such a manner as to present air passages of uniform rectangular (preferably square) cross-section, but

they also improve the appearance of the mouth of the air passage by giving it a continuous outline. When the unit has been assembled in the manner shown in Fig. 3, the front and rear edges are dipped in solder, in the manner well understood in the art, and the solder bath will unite the plaits of one wall to the opposite wall, thereby completing the unit. The solder will generally fill in the gap between the teats 10^b, 11^b and the fins 14, 13, thereby giving the edge of the unit a nicely finished appearance.

It will therefore be understood that by my invention I provide a single means for insuring uniformity of the air passages as to size and shape, and for facilitating the soldering operation. As the teats or projections 10^b, 11^b may be formed by suitable dies during the bending up of the plaits in a plaiting machine, it is possible of course, to locate such teats or projections very accurately and uniformly with reference to the plaits.

Without limiting myself to the precise construction shown, I claim:

1. A radiator unit, comprising opposite sheet metal side walls having their front edge portions offset in opposite directions to increase the width of the front edge of the unit, relative to the main portion of such unit, a series of plaits extending from each side wall into abutment with the main portion of the opposite wall, said plaits being alternately arranged and extending across said offset portions at the front edge of the unit, and being of substantially uniform width throughout their length, and inwardly extending teats or projections bent up from said offset edge portions, and arranged transversely of the latter in line with the extremities of the plaits at the front edge of the unit, and in approximate contact with said plaits, whereby said teats indicate the proper relative adjustment of the side walls in assembling, and facilitate the formation of continuous mouths for the air passages when the parts of the unit are soldered together; substantially as described.

2. A radiator unit, comprising opposite sheet metal side walls having their front edges offset in opposite directions to increase the width of the front edge of the unit, plaits extending from each side wall into contact with the main portion of the opposite side wall, said plaits being alternately arranged and being of uniform width throughout their length so as to present substantially straight free edges, said plaits extending across the offset edge portions of the side walls, teats or projections extending completely across said offset edge portions, and projecting inwardly from said offset portions into approximate contact with the free edges of the plaits at the front

edge of the unit, and projections on the main portion of each side wall arranged on opposite sides of each plait, and forming between them a seat for the free edge of 5 such plait, said seats being located adjacent said teats or projections, and having their bottom portions in the plane of the apices of said teats or projections, whereby the free edge of each plait has a full

bearing on the opposite side wall; substantially as described. 10

In witness whereof, I have hereunto set my hand on the 2nd day of April, 1913.

GARDNER E. WHEELER.
